FIGURE 1 is a top perspective view of a combined toothbrush holder and tumbler showing my new design.

FIGURE 2 is a top plan view thereof.

FIGURE 3 is a side elevational view thereof.

FIGURE 4 is an end elevational view thereof.

FIGURE 5 is an end elevational view of a modified form thereof.

FIGURE 6 is a top plan view of FIGURE 5.

FIGURE 7 is a side elevational view of FIGURE 5.

FIGURE 8 is an end elevational view of FIGURE 5.

The dominant features of my design reside in the full-line portions of the drawing, and the tumbler shown in broken lines in FIGURES 1, 4, 5 and 8 is for illustrative purposes only.

I claim:

The ornamental design for a combined toothbrush holder and tumbler, substantially as shown and described.
